BRUSH ADJUSTING MECHANISM FOR CARPET SWEEPERS

Filed Aug. 4, 1937

2 Sheets-Sheet 2

Fig. 9.

INVENTOR.
Earle R. Smith
BY
Edwin D. Jones
ATTORNEY.

a position in which an arrow 60 on the ferrule points to the legend "Low" on the exterior of the socket member 51 (Fig. 1), and wherein the pin 54 repose in the recess 57 to lock the handle against accidental turning movement.

To effect a high adjustment of the brush the handle is first depressed to remove the pin 54 from the recess 57 and then turned from the "Low" position until it reaches a circumferential position of adjustment in which the arrow 60 points to the legend "High" on the socket member. In this position of the handle the pin 54 rises into the recess 57^a to lock the handle in this "High" position of adjustment. Concurrently with such turning movement of the handle the ferrule is likewise turned causing the lugs 56 to engage the lugs 49 and thus rotate the disk 48. Rotation of the disks pulls the wires 41 in opposite directions to simultaneously elevate both loops 40 thereby raising the hangers 25 and the brackets 24 against the tension of the springs 36 and thus elevating the brush to its high position of adjustment.

Manifestly, to restore the brush to its low position of adjustment the handle is first depressed in the socket and then turned to remove the pin 54 from the recess 57^a and into the recess 57. This relieves the wires 40 and 41 of any pull and allows the hangers and brackets to return to lowered position under the action of the springs 36. Should the handle be turned further than that actually required to lower the brush, the pin 54 will rise automatically into the recess 57, thus preventing accidental detachment of the handle from the bail. By depressing the handle and at the same time turning it so that the arrow 60 points to the legend "Out" (Fig. 1), the pin is moved out of the recess and into the vertical end of the groove thereby allowing detachment of the handle from the bail.

It is significant that in this embodiment of my invention the brush adjusting mechanism permits free floating movement of the brush in both positions of adjustments thereof, and thus irrespective of the brush adjustment, the brush pulleys are at all times free to maintain positive driving contact with all floor wheels during both directions of movement of the sweeper over a floor.

Referring now to Figs. 7, 8 and 9, I have here shown a brush adjusting mechanism adaptable to a carpet sweeper in which the brush is non-floating. As in Figs. 1 and 2 such a sweeper embodies a casing 61 having at each end an end wall 62 generally of wood and a cover plate 63 generally of metal and having its vertical portion spaced from the end wall and its top portion extended over to the end wall but formed with a recess 64 through which the respective end portion of a bail L' is extended.

The bail L' is identical in construction to the bail L in the first form of my invention, except the end is flattened inwardly from its outer side and the opening 43^a for the wire or cable 41^a is disposed to the outer bail side. The bail end is pivoted on a stud 65 secured in the end wall 62 and also carried on the stud is a bail stabilizing disk 66. This disk is conventional in carpet sweepers and is for the purpose of preventing free oscillation of the casing on the bail to eliminate jumping of the casing on the floor.

The sweeper also includes the usual brush B', at each end of which is a pulley 18^a disposed between the respective floor wheels 17^a, and formed with a bearing 67 for a pintle 68. The 75

pintle is secured to a hanger 69 which is mounted for vertical movement at the outer side of the cover plate 63 by a stud 70 secured to the hanger and operating in a slot 71 of the cover plate, and a small stud 72 secured to the cover plate and extending into a slot 73 in the hanger. The hanger is made of spring metal so that it may be flexed outwardly as shown in broken lines in Fig. 8, to remove the pintle 68 from the bearing 67 and thereby allow detachment of the brush from the casing.

At the inner side of the cover plate 63 the stud 70 carries a flanged disk 74 and a sleeve 75, both formed preferably of fiber. On the disk bears the medial portion of a spring 76 for urging the hanger downwardly to cause the brush to occupy a low position of adjustment. This spring is secured at its ends to the end plate by lugs 77, as shown in Fig. 9, the flange of the disk confining the spring on the disk. Around the stud 70 and between the sleeve 75 and the stud head is looped the end of the respective wire or cable 41^a. In this manner the wire is permanently connected to the stud and in turn to the hanger, so that when the wire is pulled upwardly, the hanger is elevated against the tension of the spring 76 to lift the brush to its high position of adjustment.

It will be understood that there are two wires 30 41^a and two vertical slideable hangers 69, and that the two wires are operatively connected to the sweeper handle in the same mechanism as in the first form of my invention. Hence, the brush can be moved by operation of the handle 35 to secure low and high adjustments of the brush B'.

As shown in Fig. 9, the slot 71 is of triangular form to provide inclined side edges either of which functions to cam the stud 70 upwardly 40 when the stud is pulled laterally upwardly by the wire 41^a should the bail be in an inclined position to either side of the sweeper when actuating the handle. It will be understood that if the bail is to either side of a vertical position 45 when the handle is turned to effect a high adjustment of the brush, the wires 41^a will exert pulling forces upwardly but mostly to the side of the studs because of the angular relation of the wires to the studs. Thus, if straight slots 50 were used instead of the triangular slots, the studs would bind in the slots preventing the required upward movement of the hangers, but with the triangular slots their side edges serve to cam the studs upwardly thus elevating the hangers as required to secure the high adjustment 55 of the brush.

Although I have herein shown and described only two forms of brush adjusting mechanisms for carpet sweepers embodying my invention, it is 60 to be understood that various changes and modifications may be made herein without departing from the spirit of my invention and the spirit and scope of the appended claims.

I claim:

65 1. In a carpet sweeper; a casing; a brush in the casing having pulleys and journals thereon; hangers mounted for vertical movement on the casing; brackets pivoted on the hangers to occupy either of two extreme positions; elongated bearings on the brackets receiving the journals, said bearings occupying a horizontal position when the brackets are in one extreme position and vertical position when the brackets are in the other extreme position; means for urging the hangers downwardly to cause the brush to

occupy a low position of adjustment; and means to secure a high position of adjustment of the brush.

2. In a carpet sweeper; a casing; a brush movable vertically in the casing; hangers having pintles rotatably supporting the brush; studs on the hangers; slots in the casing receiving the pintles and studs to allow vertical movement of the hangers on the casing; springs for urging the hangers downwardly to cause the brush to occupy a low position of adjustment; a bail pivoted on the casing; wires connected to the studs and extending into the bail; a handle mounted for movement on the bail; and a connection between the handle and wires by which the wires can be actuated through movement of the handle relative to the bail to elevate the hangers and secure a high adjustment of the brush, the slots for the studs having inclined side edges by which the studs are cammed upwardly under any lateral pulling force exerted by the wires.

3. In a brush adjusting mechanism for carpet sweepers; a bail of tubular form; a socket on the bail; a handle rotatable in the socket; wires extending through the bail; a rotatable element in the bail operatively connected to said wires so that when rotated it will actuate the wires; and an operative connection between said element and said handle by which through rotation of the handle in the socket actuation of said element can be effected, said connection comprising lugs on said handle and lugs on said element disposed at an angle to the handle lugs and in the path of movement thereof when the handle is rotated.

4. In a brush adjusting mechanism for carpet sweepers; a bail of tubular form; a connector on the bail having a socket; a handle having a ferrule secured thereto and rotatably received in the socket; a bayonet groove in the socket having an open end and a recess in its upper wall adjacent its open end; a spring in the connector for urging the ferrule outwardly of the socket; a pin on the ferrule disposed in said groove to resist the urging action of the spring and frictionally retain the ferrule in certain circumferential position of adjustment; the pin adapted to engage within the recess for latching the ferrule against turning the pin to the open end of the groove; wires in the bail; and a connection between the ferrule and wires by which the wires can be pulled upon circumferential adjustment of the ferrule.

5. In a brush adjusting mechanism for carpet sweepers as embodied in claim 4, wherein said connection comprises a disk rotatable in the connector opposite the socket and to which the wires are connected; lugs on the ferrule; and lugs on the disk disposed in the path of movement of the ferrule lugs when the ferrule is rotated to rotate the disk and thus actuate the wires.

6. In a carpet sweeper; a casing; a brush movable vertically in the casing; hangers having pintles rotatably supporting the brush; studs on the hangers; slots in the casing receiving the pintles and studs to allow vertical movement of the hangers on the casing; springs for urging the hangers downwardly to cause the brush to occupy a low position of adjustment; a bail pivoted on the casing; wires connected to the studs and extending into the bail; a handle mounted for movement on the bail; and a connection between the handle and wires by which the wires can be actuated through movement of the handle relative to the bail to elevate the hangers and secure a high adjustment of the brush.

7. In a carpet sweeper, a casing, a rotary brush in the casing, means associated with the casing for supporting the brush and movable vertically relative to the casing whereby the brush may be adjusted to high and low positions with respect to the surface to be cleaned, a bail pivotally mounted on said casing, a handle movably carried by said bail, flexible means connected to the sweeper handle and to the brush supporting means at substantially the axis of rotation of the sweeper bail whereby movement of the bail is independent of movement of said brush supporting means, and spring means normally urging said brush supporting means to a low position, said flexible means being connected to said brush supporting means at such point that a pull on said flexible means is effective to move said brush supporting means against the tension of said spring means, said handle being movable relative to the sweeper bail to actuate the flexible means to effect a high or low adjustment of said brush supporting means and brush.

8. In a carpet sweeper, a casing, a rotary brush in the casing, means associated with the casing for supporting the brush and movable vertically relative to the casing whereby the brush may be adjusted to high and low positions with respect to the surface to be cleaned, a bail pivotally mounted on said casing, a handle movably carried by said bail, means connected to the sweeper handle and to the brush supporting means at substantially the axis of rotation of the sweeper bail whereby movement of the bail is independent of movement of said brush supporting means, and resilient means normally urging said brush supporting means in one direction, said connecting means being connected to said brush supporting means at such point that a pull on said connecting means is effective to move said brush supporting means against the action of said resilient means in an opposite direction, said handle being movable relative to the sweeper bail to actuate the connecting means to effect an adjustment of said brush supporting means and brush.

9. In a carpet sweeper, a casing, a rotary brush in the casing, means associated with the casing for supporting the brush and movable vertically relative to the casing whereby the brush may be adjusted to high and low positions with respect to the surface to be cleaned, a bail pivotally mounted on said casing, a handle movably carried by said bail, flexible means connected to the sweeper handle and to the brush supporting means at substantially the axis of rotation of the sweeper bail whereby movement of the bail is independent of movement of said brush supporting means, spring means normally urging said brush supporting means in one direction, said flexible means being connected to said brush supporting means at such point that a pull on said flexible means is effective to move said brush supporting means against the tension of said spring means, said handle being movable to predetermined positions relative to the sweeper bail to actuate the flexible means to effect an adjustment of said brush supporting means and brush, and additional means associated with the handle and bail to limit the movement of the handle to the adjusted high and low positions.

10. In a carpet sweeper, a casing, a rotary brush in the casing, means associated with the casing for supporting the brush and movable vertically relative to the casing whereby the brush may be adjusted to high and low positions with

respect to the surface to be cleaned, a hollow bail pivotally mounted on said casing, a handle carried by and rotatable with respect to said bail, flexible means extending through said hollow bail and connected to the sweeper handle and to the brush supporting means at substantially the axis of rotation of the sweeper bail whereby movement of the bail is independent of movement of said brush supporting means, and spring means normally urging said brush supporting means in one direction, said flexible means being connected to said brush supporting means at such point that a pull on said flexible means is effective to move said brush supporting means in an opposite direction against the tension of said spring means, said handle being rotatable relative to the sweeper bail to actuate the flexible means to effect an adjustment of said brush supporting means and brush.

11. In a carpet sweeper, a casing, a rotary brush in the casing, means associated with the casing for supporting the brush and movable vertically relative to the casing whereby the brush may be adjusted to high and low positions with respect to the surface to be cleaned, a bail pivotally mounted on said casing, a handle movably carried by said bail, a flexible loop connected to the brush supporting means substantially at the pivotal axis of said bail, flexible means connected to the sweeper handle and to said loop adjacent the pivotal axis of said bail whereby movement of the bail is independent of movement of said brush supporting means, and spring means normally urging said brush supporting means in one direction, said flexible means being connected to said brush supporting means at such point that a pull on said flexible means is effective to move said brush supporting means in an opposite direction against the tension of said spring means, said handle being movable relative to the sweeper bail to actuate the flexible means to effect an adjustment of said brush supporting means and brush.

12. In a carpet sweeper, a casing, a rotary 45

brush in the casing, brush supports associated with the casing and slideable vertically relative thereto whereby the brush may be adjusted to high and low positions with respect to the surface to be cleaned, said brush supports each having a stud engaged with an inclined guide on said casing so arranged that said brush supports are moved in a vertical direction when a pull laterally upward is exerted on the studs, a bail pivotally mounted on said casing, a handle rotatably carried by said bail, flexible means connected to the sweeper handle and to said studs on said brush supports, and spring means normally urging said brush supports in one direction, 10 said flexible means being adapted to exert a pull on said studs when the handle is actuated to move said brush supports in an opposite vertical direction.

13. In a carpet sweeper, a casing, a rotary brush in the casing, a bail pivotally mounted on said casing, a connector secured to said bail, means in the bail and on the casing to adjust the brush with respect to the surface to be cleaned, said connector having a slot therein with limit stops corresponding to the adjusting positions for the brush, and a handle adapted to be removably inserted into the connector, said handle having means cooperating with the slot and the limit stops and being adapted to actuate the first-mentioned means to such adjusted positions of the brush limited by the stops.

14. In a carpet sweeper, a casing, a rotary brush in the casing, a bail pivotally mounted on said casing, a connector secured to said bail, means in the bail and on the casing to adjust the brush with respect to the surface to be cleaned, and a handle adapted to be removably inserted into the connector, said connector and handle having a pin and slot connection therebetween with limit stops in the slot corresponding to the adjusting positions for the brush, and said handle being adapted to actuate the first-mentioned means to such adjusted positions of the brush limited by the stops.

TREATMENT OF MOLTEN ALUMINUM AND
ITS ALLOYS

Philip T. Stroup, New Kensington, Pa., assignor to
Aluminum Company of America, Pittsburgh,
Pa., a corporation of Pennsylvania

No Drawing. Application August 2, 1939,
Serial No. 288,031

5 Claims. (Cl. 75—68)

This invention relates to the treatment of molten aluminum and its alloys for the purpose of removing certain impurities therefrom.

In producing commercial aluminum base alloys, it is often desirable to use varying amounts of aluminum and aluminum base alloy scrap metal in order to reduce the proportion of virgin aluminum that would otherwise be required and as well as to prevent an undue accumulation of scrap material. The term "scrap metal," as here employed, refers to aluminum and aluminum base alloys that have been employed in some previous fabricating operation. Certain of the elements found in scrap metal are frequently useful in making the desired alloy, while other elements are in some cases undesirable, if not deleterious to the properties of the final product. It is, therefore, necessary to either select suitable scrap metal free from the undesired elements or to treat the metal in some way to reduce or eliminate these elements altogether. Such undesired elements are here considered to be impurities with respect to the alloy being produced, whether or not they have a detrimental effect upon the alloy.

It should be emphasized that such elements as are herein termed undesirable may sometimes be intentionally added in controlled amounts to produce specific characteristics in an aluminum base alloy, but they may be regarded as generally undesirable when the said specific characteristics are not required.

Various general methods of fluxing molten aluminum and its alloys have been used heretofore, but no commercially feasible method has been known for substantially eliminating the impurities antimony, bismuth, lead, and tin, which may be introduced through the use of scrap metal. Since at times it may be necessary to use some scrap metal, which contains these impurities, in making a final alloy that should be substantially free from these elements, it is desirable to be able to eliminate these impurities during the melting operation. The elimination of these impurities is especially important in the case of certain aluminum base alloys because it has been found that the desired properties are more difficult to obtain in these alloys if more than a few hundredths of a per cent of these impurities are present.

My invention is directed to a method of purifying or refining molten aluminous metal with respect to antimony, bismuth, lead, and tin impurities. More specifically, the object of my invention is to provide a method for effecting a

substantially complete removal of these metallic impurities from aluminum and aluminum base alloys by a simple treatment in the melting room. A further object is to provide a commercially feasible treatment of molten aluminum alloys into which antimony, bismuth, lead, and tin impurities have been introduced through the use of scrap metal. Another object is to provide a method of effecting the removal of these undesired elements without appreciably disturbing the proportions of the desired alloying ingredients.

It has been discovered that the addition of sodium to a melt of aluminum or aluminum base alloy containing relatively small amounts of one or more of the elements antimony, bismuth, lead, and tin, serves to substantially eliminate these elements from the melt in the form of insoluble compounds. By "substantial elimination" I mean that these impurities are either reduced to a trace or at least below an amount which would be injurious to the final alloy. The sodium may be added in any suitable manner so long as it is held below the surface of the melt and the melt is sufficiently agitated to permit the distribution of the sodium throughout the molten mass. The amount of sodium required to effect the removal of these impurities usually falls between 0.1 and 1 per cent, depending upon the amount of the impurities present, which in most instances is less than 1 per cent. Under these conditions a single treatment with sodium is ordinarily sufficient to effect the substantial elimination of antimony, bismuth, lead, and tin. However, the treatment may be repeated, if necessary.

The sodium introduced into the molten bath appears to form insoluble compounds with the impurities. These compounds accumulate on the surface and/or settle to the bottom of the bath. If more sodium is added than the amount required to remove the impurities, the excess will escape from the melt by rising to the surface and passing off with the dross or in the form of vapor, or it can be removed by methods known in the art.

In carrying out my invention in the preferred form, the charge of metal containing antimony, bismuth, lead, or tin impurities is first melted. While the charge is still molten, a small amount of metallic sodium is thrust into the melt and held at the bottom of the charge by means of an inverted, perforated cup mounted on the end of a rod. The perforated cup is held in this position until the sodium has completely melted and passed into the bath, whereupon the cup is stirred
